EMERGENCY KEY FOR DOOR LOCKS

William H. Wilson, Somerville, Mass.

Application February 21, 1939, Serial No. 257,770

6 Claims. (Cl. 70—429)

This invention relates to keys and particularly to keys for use in the mortise locks of doors inside a building.

The stem or shank of the key embodying the present invention is provided with a threaded extension projecting through and beyond the outer surface of the door and on this projecting portion is mounted means whereby the removal of the key from the lock is prevented, while permitting sufficient movement about the axis of the stem to lock or unlock the door.

Means is also provided on the projecting portion of the extension whereby the key may be turned from the outside of the door to unlock the same.

A freely rotatable guard member surrounds the outwardly projecting portion of the key which is adapted to prevent the turning of the key from the outside except by those provided with a suitable turning implement.

The object of the invention is the provision of an emergency key which may be used to unlock from the outside the door of a bathroom or similar room in case an accident occurs therein.

A further object of the invention is the provision of means whereby children playing in the room cannot remove the key from the lock.

These objects are attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

40 Of the drawing

Figure 1 represents the edge of a door having a mortise lock mounted therein in which is disposed an emergency key embodying the principles of the present invention.

45 Figure 2 represents an elevation of said emergency key with portions thereof shown in section.

Figure 3 represents an elevation of a blank having a rectangular bit which may be notched to fit any mortise lock.

Figure 4 represents an end elevation of said emergency key.

Figure 5 represents an elevation of a collar mounted on the extension of said emergency key.

55 Figure 6 represents an elevation of a member disposed in said collar and threaded to said extension.

Figure 7 represents another member adapted to be threaded to the key extension and contact-

ing with the outer face of the member shown in Fig. 6.

Fig. 8 represents an elevation of a guard member or casing surrounding the members shown in Figs. 6 and 7.

Fig. 9 represents an elevation of an implement such as a clock key adapted to coact with flattened sides at the outer end of said key extension.

Figure 10 represents an end elevation of the 10 implement shown in Fig. 9, and

Figure 11 represents an enlarged view of the outer end of the key extension having flat sides and threaded portions at the corners thereof.

Similar characters indicate like parts throughout the several figures of the drawing.

In the drawing, 10 is a key provided with a stem or shank 11 at one end of which is a ring 12 by which the key may be turned in a mortise lock.

Near the opposite end of the main stem or shank 11 is a bit 13 which is provided with notches 14 so constructed that it will coact with a mortise lock 15 of usual construction inserted in the edge of a door 16.

The outer end of the stem or shank 11 has a 25 threaded extension 17 which extends through the mortise lock 15 and the door 16, a portion of this extension 17 projecting beyond the outer face of the door 16.

Threaded to the projecting portion of the stem or shank 11 is a cup-shaped member 18, the outer end thereof having a tubular portion which is spaced from the extension 17 a sufficient distance to admit the operating end of an implement 19 35 adapted to coact with the flat sides 20 at the extreme outer end of the extension 17.

Surrounding this tubular member 18 is a guard member or casing 21 which is freely revoluble and prevents any unauthorized person without an 40 implement 19 from turning the cup-shaped member 18 after it has been properly adjusted on the threaded extension 17.

The inner end of this guard member 21 is forced into a cup-shaped collar 22, the closed end 45 of which contacts with the outer face of the door.

When the key is disposed in the mortise lock 15 and the guard member 21, 22 is positioned around the cup-shaped member 18, the threads of said cup-shaped member 18 engaging the 50 threads of the extension 17 will prevent the key 10 from being removed from the lock, while at the same time the key has sufficient movement about the axis of the stem 11 to permit the door 55 being locked and unlocked.

As a consequence, children going into a bathroom and playing therein cannot remove the key 10 from the door as very often happens, the children dropping the key on the floor and then be- 60

ing unable to insert the same again into the lock 15.

When this happens the children are locked in the room and can only be released therefrom by someone climbing up a ladder to the window of the room and through the same, or by forcing the door inwardly causing considerable damage thereto.

Moreover, it is often the case that accidents often occur to elderly people or cripples while in the bathroom with the door locked.

By supplying an emergency key such as is shown and described herein, an occupant of the house may take a clock key 19 or some similar implement and by engaging the operating end thereof with the flat sides of the extension 17 the door may be unlocked and access to the room obtained whereby the injured party may be removed or permitting the children locked in the 20 room to escape therefrom.

These keys may be provided for the inner doors of bathrooms when the house is first built or they may be provided later when the necessity for the use of the same occurs.

25 With healthy people occupying the home the ordinary lock key may be used but when later small children arrive and elderly or invalid persons form a part of the household, it is desirable to remove the usual key and substitute therefor one of these emergency keys as shown and described.

In such a case, the key is removed and taken to a locksmith who will be provided with blank keys the bits of which are rectangular. All the 35 locksmith has to do is to make the rectangular blank bit conform to the bit of the ordinary key of the lock and then the emergency key will be substituted for the ordinary key which came with the lock.

40 Usually in every house there are plenty of clock keys, and generally these are of a size to fit the squared portion of the extension 17.

A clock key 19 similar to that shown in the drawing may be hung on a nail at some convenient place where it would be accessible whenever its use was necessary.

The projecting portion of the extension 17 extends only a short distance from the outer surface of the door and is never conspicuous and this is particularly true in as much as it is disposed immediately beneath the door handle 23 which is much larger and extends outwardly from the door a much greater distance.

55 In assembling the emergency key 10 in the lock 15 the cup-shaped member 22 is placed around the extension 17 and then the member 24 is screwed onto said extension thereby moving the member 22 into near contact with the outer face of the door 16 or into near contact with the plate 25 where the door is provided with such plate.

60 This collar or cup-shaped member 22 must always be permitted to turn freely about the axis of stem 11 of the key 10.

The member 24 is provided with a boss 26, 65 which being disposed in the keyhole of the lock 15 supports the extension 17.

When the member 24 has been properly adjusted on the extension 17, the member 18 is screwed onto the extension 17 and against the outer face of the member 24 forming a lock nut.

70 The guard member 21 is then positioned about the member 18 with its inner end driven tightly

into the collar 22 so that the members 21, 22 will always rotate together.

The member 21 has an inner shoulder 27 which is in close proximity to the flange 28 of member 18, thus preventing any outward movement of member 18 when the members 18, 21, 22 and 24 have been assembled on the threaded extension 17.

Where the extension 17 is provided with the flat sides 20, portions of the thread of said extension extend to the outer end of said extension at the corners 29 of said flattened portion, as shown in Fig. 11.

When the emergency key is in use it can lock and unlock the door but cannot be removed from the lock which obviously is a great advantage.

Another great advantage in the use of this emergency key is in providing a means whereby the door of a room may be opened from the outside when any accident occurs within the room.

If desired, the bit 13 of the key may be so notched as to form a skeleton key which may be used on the mortise lock of any inner door of a building.

It is believed that the operation and many advantages of the invention will be understood without further description.

Having thus described my invention, I claim:

1. A key for mortise locks of doors having integral therewith a threaded extension alined with the body portion of said key and projecting beyond the outer face of the door, the outer end of said extension having flat sides, and a cup-shaped member threaded to and surrounding the projecting portion of said extension.

2. A key as set forth in claim 1 in which a freely revoluble casing surrounds the projecting portion of said extension and encloses said cup-shaped member.

3. A key as set forth in claim 1 in which a freely revoluble casing surrounds the projecting portion of said extension and encloses said cup-shaped member, said casing consisting of a tube, and a cup-shaped collar secured to the inner end of said tube and adapted to bear against the outer face of the door.

4. A key as set forth in claim 1 in which the outer end of the cup-shaped member is spaced sufficiently from the outer end of said extension to admit a device adapted to engage the flat sides of said extension and turn the key in said lock.

5. A key for mortise locks of doors having integral therewith at one end a ring by which said key may be turned and at the opposite end an alined extension, the diameter of which is less than the diameter of the key stem, said extension projecting through and beyond the outer face of the door, and removable means on the outer end of said extension whereby the key is prevented from removal from the lock.

6. A key for mortise locks of doors having integral therewith at one end a ring by which said key may be turned and at the opposite end an alined extension, the diameter of which is less than the diameter of the key stem, said extension projecting through and beyond the outer face of the door, and removable means on the outer end of said extension whereby the key may be turned freely in the lock by means of said ring but is prevented from removal therefrom.
